UNITED STATES PATENT OFFICE.

JOHN J. USHER, OF ST. HELENS, OREGON, ASSIGNOR TO ST. HELENS IRON & MARINE WORKS, OF ST. HELENS, OREGON, A CORPORATION OF OREGON

CABLE CLAMP.

Application filed February 4, 1927. Serial No. 165,935.

The present invention is directed to improvements in cable clamps.

The primary object of the invention is to provide a device of this character that can be effectively used in connection with cable wires of different sizes.

Another object of the invention is to provide a clamp including a pair of gripping blocks capable of being easily and quickly adjusted to present cooperative cable receiving grooves of various sizes in order that the cables of different sizes can be effectively gripped.

Another object of the invention is to provide a device of this character so constructed as to automatically grip the cable when strain is applied to the device, the gripping action being increased upon the cable as strain is increased upon the device.

20 In the accompanying drawing:

Figure 1 is a side elevation of the device.

Figure 2 is a sectional view on line 2—2 of Figure 1, looking in the direction of the arrows.

25 Figure 3 is a sectional view on line 3—3 of Figure 1.

Figure 4 is a perspective view of one of the clamping blocks.

The device comprises a pair of levers 1, 30 pivotally connected at their forward ends by a bolt 2, the rear ends of said levers being provided with furcations 3, grooved rollers 4 being rotatably mounted therebetween.

The levers are provided with lateral 35 bosses 5 having formed therein recesses 6, the end walls of which being provided with grooves 7, the purpose of which will be later explained.

Clamping blocks 8 are employed and are 40 removably mounted in their recesses 6, said blocks having lugs 9 upon their ends for engaging the grooves 7 in the end walls of the respective recesses, and when thus engaged lateral displacement of said blocks 45 is prevented.

The blocks are rectangular in cross section and have their side faces formed with longitudinal grooves 10, varying in size for use in connection with cables, or wires of 50 different gage.

In order to more firmly grip a wire or cable certain of the block faces may be provided, respectively, with a transverse groove and rib 11 and 12. It will be apparent that when the gripping blocks are

engaged with the wire or cable it will be firmly gripped in selected grooves 10 and if engaged between the spaces provided with the respective groove and rib 11 and 12, the wire or cable will be clinched in order 60 to more firmly grip the same. The block shown in Figure 4 is the one having the transverse ribs 12 and when engaged with a transverse groove will effectively grip the cable. The ribs are provided with grooves 65 14 which aline with the associated grooves 10.

By locating the bosses 5 in offset relation with respect to the levers the cable or wire engaged by the gripping blocks will extend 70 longitudinally of the levers 1 and will not lie between the outer ends of said levers and interfere with the free operation of the drawing cable 15. This cable, as shown in Figure 1, is trained around the wheels 4 75 and obviously, when strain is applied thereto, the levers will be moved toward each other to enable the gripping blocks to bindingly engage the cable.

As shown in Figure 1, a comparatively 80 large cable is being drawn and at which time the grooves 10 employed are of a size to effectively receive the cable. Upon applying strain to the cable 15 the levers 1 will be drawn toward each other, thus causing 85 the blocks 8 to firmly grip the cable. When it is desired to draw a small cable or wire, it will be of course understood that the blocks 8 are removed from the respective recesses and replaced with selected 90 grooves 10 of the proper sizes confronting each other.

From the foregoing description it will be seen that a clamp has been provided which can be manufactured at a small cost 95 and which is capable of being used in connection with telegraph and fence wires, or with cables or rope used in building constructions, mining or logging.

Having thus described the invention, I 100 claim:

1. A device of the class described comprising a pair of pivotally connected levers, bosses carried by the levers and having recesses formed therein, the end walls of the 105 recesses being provided with grooves, cable gripping blocks removably and adjustably mounted in the recesses and having lugs upon their ends for detachable engagement with said grooves.

2. A device of the class described comprising a pair of pivotally connected levers, a boss on each lever, each boss having a recess therein, a gripping block removably mounted in each recess and having its face formed with cable-receiving grooves varying in size, the blocks being provided, respectively, with a transverse rib and a trans-

verse groove, said blocks being adapted to be adjusted to place a groove of one block 10 in registration with a similar groove of the other block and one rib of one block in the transverse groove of the other block.

In testimony whereof I affix my signature.

JOHN J. USHER. [L.S.]
